UNITED STATES PATENT OFFICE.

JACOB ROSENBERG, OF NEW YORK, N. Y.

DESIGN FOR A LIQUID-RECEPACLE.

SPECIFICATION forming part of Design No. 30,534, dated April 11, 1899.

Application filed March 16, 1899. Serial No. 709,342. Term of patent 14 years.

To all whom it may concern:

Be it known that I, JACOB ROSENBERG, a citizen of the United States, residing in the city, county, and State of New York, have invented and produced a new and original Design for Liquid-Receptacles, of which the following is a specification, reference being had to the accompanying drawings, forming a part thereof, in which—

10 Figure 1 is a perspective view, and Fig. 2 is a horizontal section on the line *xx*.

The leading and material feature of my design is the liquid-receptacle made the subject of the illustration herein.

15 The base 1 is circular in form and has rising from it the pedestal 2 of the receptacle proper, 3. The said receptacle bulges abruptly from a point a short distance above the upper end of the pedestal 2 and is polygonal 20 in cross-section, as shown. Adjacent to the widest part of the receptacle and in substantially the same horizontal plane is arranged a series of radially-disposed faucets 4, having downwardly-extending spouts 5. From a

point a short distance above the faucets 4 the 25 sides of the receptacle gradually converge until they merge into a substantially cylindrical neck 6, from the upper end of which extends a plurality of supplemental angularly-arranged sides or mouthpieces 7, the side 30 edges of which are in contact with each other and the upper edges of which are rounded.

By the term "liquid-receptacle" used in this specification it will of course be understood that I intend to include such receptacles as water-bottles, carafes, decanters, and the like.

Having now described the invention, what I claim is—

The design for a liquid-receptacle, substantially as shown and described.

In testimony whereof I affix my signature in the presence of two witnesses.

JACOB ROSENBERG. [L. S.]
